WITNESS:

Victor J. Evans

ATTORNEY

UNITED STATES PATENT OFFICE.

DEWITT C. DUNHAM, OF MARYSVILLE, CALIFORNIA.

GRAPE-PICKING KNIFE.

Application filed January 16, 1924. Serial No. 636,607.

To all whom it may concern:

Be it known that I, DEWITT C. DUNHAM, a citizen of the United States, residing at Marysville, in the county of Yuba and State 5 of California, have invented new and useful Improvements in Grape-Picking Knives, of which the following is a specification.

The object of this invention is the production of a hand operated knife for severing 10 bunches of grapes from vines in vineyards so that this operation can be quickly and easily performed and a greater amount of grapes can be picked than by the ordinary means.

15 With the foregoing and other objects in view, which will present themselves as the nature of the invention is better understood, reference will be had to the drawing which accompanies and which forms part of this 20 application.

In the drawing:—

Figure 1 is a perspective view showing the improvement in operative position upon the hand of a grape picker.

25 Figure 2 is an approximately central longitudinal sectional view through the clamp element of the improvement looking toward the knife.

Figure 3 is a sectional view on the line 30 3—3 of Figure 2.

Figure 4 is a longitudinal section of the hand engaging portion of the device.

As disclosed by the drawing, my improvement 35 comprises a hand clamp which is preferably formed from a single sheet of metal to include an approximately straight body portion 1 whose ends are rounded toward each other, as indicated by the numerals 2 and 3. The edges of the body, and if 40 necessary, those of the ends are flared outwardly or beaded, as at 4, so that the clamp will not inflict injury to the hand of the operator.

By reference to the drawing, it will be 45 seen that the rounded end 2 is extended from only one edge of the body 1 and also that the body from the end 3 is widened to the said end 2. The portion above the rounded clamp provided by the end 2 is bent upon 50 itself to provide a cross sectionally U-shaped extension 5, and in this U-shaped extension there is pivoted, as at 6, one end of a blade 7. The blade is, of course, limited in its movement in one direction by contact with 55 the connecting wall of the U-shaped exten-

sion 5. The blade preferably has its cutting edge, adjacent to its outer end, arched inwardly, as at 8, and the said blade has secured thereon a finger ring 9 extended inwardly and laterally thereof.

60 There is preferably riveted or otherwise secured to the metal hand clamp a leather strap or band 10. One end of the strap is provided with a buckle, and the opposite end is apertured to receive the tongue of the buckle therethrough whereby the strap 65 may be adjustably secured on the hand of the operator. In order to prevent the ends of the strap contacting with the hand of the operator, there is secured on the inner face, 70 adjacent to one end of the said strap, a fabric flap 11.

In operation, the clamp is strapped around the hand of the user, the body 1 of the clamp being arranged over the back of the hand, and the rounded ends 2 and 3 are 75 arranged over the back of the user's hand. The clamp materially assists the strap in sustaining the device in proper adjusted positions on the hand of the operator.

80 The index finger of the user is slipped through the ring 9, and by moving this finger toward his thumb, which is in contact with the stem of a bunch of grapes, the said stem may be readily severed from the vine. With my improvement, I have found from practice that a far greater amount of grapes can be harvested than with any other device with which I am 85 acquainted, and it is thought that the foregoing description, when taken in connection with the drawing, will fully set forth the simplicity and advantages of the improvement.

90 Having described the invention, I claim:—

In a grape stem cutter, a clamp formed of metal to provide a body whose ends are rounded toward each other, and the edges of the body being flared outwardly, said body having one of its ends of a greater width than the other and bent upon itself, from its referred to rounded portion, to provide an extension which is U-shaped in cross section, a blade pivoted therein, and an inwardly disposed laterally extending finger receiving ring fixed on the blade.

100 105 In testimony whereof I affix my signature.

DEWITT C. DUNHAM.
